UNITED STATES PATENT OFFICE

2,438,295

CLIP FOR FORMING NECKTIES

Harley Walker Morden, Toronto, Ontario, Canada, assignor of fifty per cent to Harry H. Gies, Toronto, Ontario, Canada

Application August 11, 1944, Serial No. 549,040

1 Claim. (Cl. 2—152)

1

The invention relates to a clip and retainer for fabric materials and more particularly for neckties and the like.

The object of the invention is to provide a clip for retaining foldable materials in predisposed position.

A further object of the invention is to provide an adjustable clip and retaining member for maintaining fabric materials and the like in predisposed position with the least possible handling of the materials.

More particularly it is an object of this invention to furnish a clip and retaining means which may be used to form and maintain the folds and position of a necktie.

It is also an object of the invention to furnish a means of securing neckties in position without requiring that a knot be made in the necktie, thus preserving the necktie from unnecessary handling and wear.

A further object of the invention is to furnish a necktie clip to which may be secured a chain or other suitable means with which to surround and retain the loose ends of the necktie to prevent them from becoming disordered or untidy in appearance during wear.

A further object of the invention is to furnish a tie clip which is ornamental in character, is easy to adjust and being simple in structure, is efficient for its purposes.

In the drawings:

Figure 1 is a partial front elevational view of the clip.

Figure 2 is a partial side elevational view of the clip.

Figure 3 is a detailed enlarged sectional view taken on the line 3—3 in Figure 1.

Figure 4 is a view of the clip in use.

Figure 5 is a sectional view through the pivotal connection of the clip.

The general practice of securing neckties has hitherto consisted of forming a slip knot in the necktie, leaving the free ends to hang down the front of the body. This practice involves a good deal of handling of the necktie with the result that on those portions of the necktie which are habitually used to form the slip knot the necktie tends to become quickly soiled and worn. Moreover, in order to keep the slip knot of the necktie close to the top edge of the shirt collar, frequent adjustment is necessary, involving pulling of the free ends of the necktie so as to maintain it in proper position. Neckties also have a tendency to get out of centre alignment between the wings of a shirt collar, and in order to re-

2

place the necktie centrally, frequent adjustment must be made.

In order to remedy these and other defects in present necktie securing methods, the instant invention was provided, and consists of a clip unit having the framework portions 10 and 10a which may be pivotally secured as at 11 by a member 12, the latter preferably comprising the screw member 13 in threaded engagement with the pivoted portions or arms 14 and 15, which together with the pivot form the framework. The threaded engagement between the screw member 13 and the arms 14 and 15 is such as to provide for tightening the pivotal engagement between the arms thereby to tension them one to the other so that a means is formed for maintaining the arms in spread apart or open position and likewise will function to hold them in the gripping or closed position wherein they grip the fabric of a cravat. Preferably, the screw is formed with a tapered head as shown in Figure 5, where the forks 11a and 11b of arm 15 are shown mounting the tongue 14a of arm 14, the tapered head 12a of screw 12 controls friction between forks 11a and 11b and tongue 14a, and has thread means 12b designed to meet with suitable threads in fork 11a. It will be apparent due to the taper of head 12a that screw 12 will not rotate while the arm 14 is being rotated relative to arm 15.

At the extremities of the framework 10 are the enlargement portions 16 and 17 which may be of any suitable cross-sectional shape but are preferably dome shaped and may have the outer surfaces 18 and 19 ornamented. Rearwardly of the enlargement portions 16 and 17 are the cup shaped members 26 adapted to provide for frictional engagement with fabric materials, and as illustrated in Figure 2 are preferably formed so as to present in each case a serrated ridge 22 and 23 to the material.

The detailed construction of the enlargement portions 16 and 17 in relation to the serrated surfaces 22 and 23 will best be understood from Figure 3, whence it will be seen that the dome shaped members are formed with the peripheral flanges 24 which engage the upper edges 25 of the cup shaped members 26.

Secured through the members 26 is the central pin member 21, the latter being secured through the member 26 in the manner of a rivet by means of the flange 28. Surrounding the central pin member 21 is a plurality of smaller pin members 29 secured through the member 26, by flanges 30.

The arms 14 and 15 are preferably offset as at 31 in order to space the arms one from the other

when said arms are swung to the closed position so that the ends thereof grip the cravat. This is clearly shown in Fig. 2. Thus, a spacing is provided between the arms permitting portions of the cravat material to extend therebetween.

Adjacent to the pivot 11 preferably is the flexible chain member 32 for the purpose of completely surrounding the necktie or fabric, and it will readily be understood that the end portion 33 may be formed in the manner of a hook which may be inserted for securing through the aperture 34 in the frame 10.

In use, one end of the necktie 35 is folded over the opposite end 36, the wide ends of the necktie being placed adjacent to each other in the position shown at 37 in Figure 4. The clip is then placed preferably with the pivot portion 12 rearwardly of the fabric so as to partially surround it. The enlargement portions are thus located one on each side of the partially enclosed fabric.

By gently pressing the portions 18 and 19 the fabric of the necktie is first engaged by the large pin members 27 and subsequently by the smaller pin members 29, the adjacent fabric being frictionally held by the serrated surfaces 22 and 23. The member 32 may now be looped around the necktie completely surrounding it and the end 33 secured in the aperture 34.

It will be understood that changes and modifications may be made to the preferred structure described within the scope and nature of the appended claim.

What I claim as my invention is:

A clip for neckties designed to underlie a tie and to be partially concealed thereby and to hold an unknotted tie in fixed simulation of a knotted tie and comprising: a pair of arms, a tongue

formed on one end of one arm, a fork formed on one end of the other arm and adapted to receive said tongue, a screw passing through said fork and said tongue whereby said arms are pivotally connected, thread means in one of the prongs of said fork to mate with the threads of said screw, the head of said screw and the other prong of said fork including means for frictionally restraining said screw in said latter prong, said screw creating friction between said tongue and said prongs when tightened, a pair of pin-like members projecting substantially at right angles from the opposite ends of said arms and designed to project towards one another to grip a portion of said tie when the arms are swung together whereby to secure opposed portions of the tie to simulate a knot.
